SEPARATOR FOR RUNNING YARN AND LIQUID

John Watson Pedlow, Chester, Pa., assignor to American Viscose Corporation, Philadelphia, Pa., a corporation of Delaware

Application May 6, 1952, Serial No. 286,236

9 Claims. (Cl. 210—149)

The present invention relates to a device for stripping liquid from a running yarn and particularly to a device of the type which may be used in conjunction with a conduit to receive liquid and a continuous yarn traveling concurrently with the liquid.

In the spinning of regenerated cellulose yarns, for example, the filament-forming liquid may be extruded from a spinneret into a tube extending away from the face of the spinneret. The extruded liquid is coagulated by a stream of liquid coagulant fed continuously into a region adjacent the spinneret and through the tube. The material of the nascent yarn is to a considerable extent regenerated as it passes while suspended in the liquid coagulant through the tube. However, after the yarn is spun and partially regenerated, it is desirable in accordance with some of the preferred methods of yarn manufacturing to promptly separate the liquid coagulant from the yarn as quickly and efficiently as possible so that the coagulant may be returned to a reclamation system with as little dilution as possible and so that a further treatment, particularly a liquid treatment, may be applied immediately and more effectively to the yarn. A common disadvantage of stripping the liquid from the yarn is that in effecting substantial removal of the liquid, the filaments constituting the yarn are broken to such an extent as to materially effect the quality thereof. In general, the damage to the yarn increases in accordance with the efficiency and rapidity with which stripping action is performed by these devices.

It is an object of the present invention to provide apparatus for removing liquid from a running yarn rapidly and effectively without damaging the yarn. It is a further purpose to provide an apparatus of relatively small dimensions for receiving a stream of liquid from a closed duct, stripping the liquid from the yarn, and then returning the liquid to a recirculatory or waste system. It is also an object to provide an apparatus through which the yarn is easily laced and which permits facile capturing of a yarn-end whereby it may be laced readily through apparatus for applying succeeding treatments. Other objects, features, and advantages will be apparent from the following description of the invention and the drawing relating thereto in which

Fig. 1 is a section in elevation of apparatus in accordance with the present invention;

Fig. 2 is a section taken along the line II—II of Fig. 1;

Fig. 3 is a plan view of the container portion of the apparatus shown in Fig. 1 with parts removed therefrom;

Fig. 4 is a pictorial view of one of the stripping elements shown in Figs. 1 and 2; and

Fig. 5 is a pictorial view of partition member shown as a part of the apparatus in Fig. 1.

According to the present invention, a device for stripping liquid from a running strand is provided which comprises a compartment having an inlet port for the liquid and the strand, an outlet port for discharging the liquid, and at least one surface for guiding the strand as

it passes from the compartment whereby the strand is caused to follow a desired path within the compartment. Arranged in series and spaced relationship between the inlet port and the guide surface is a plurality of narrow elongated surfaces or elements extending transversely of the path which take the form of the perforate baffle extending through the compartment for the strand. Each port is contiguous with one of the two regions into which the compartment is divided by the baffle with the outlet port being located generally below the baffle to receive by gravity liquid forced through the baffle. Supported closely over the baffle along the side thereof traversed by the strand is a removable partition member which urges and implements the passage of the liquid through the baffle.

The single embodiment of the invention herein described, and illustrated in section view in Fig. 1, comprises a container or body portion 5 having a tubular extension 6 providing an inlet port for a stream of liquid and strand discharged thereinto from a tube 7 which extends within the extension 6. The container 5 is provided also with a drainage or outlet port for liquid. For this purpose, the container 5 may have, as shown, a tubular extension 9. The interior of the container 5 is divided into two regions by a plurality of rod-like elements 10 arranged in spaced and series relationship. The elements extend lengthwise between opposite walls of the container. As shown, they are arranged in an approximately straight line with the rounded surfaces thereof tangent to a plane extending from one side of the aperture 11 to the top edge of the container. The elements 10 taken as a group constitute a perforate baffle with the region of the container in which the baffle faces downwardly being contiguous with the outlet port defined by extension 9. The outlet port is disposed below the generally downwardly-facing surface of the baffle to receive all liquid between the elements 10 by gravity.

Supported immediately over the baffle comprising elements 10 is a partition member 14 having a handle 15 and a channeled surface 16. The channel or groove 16a within the surface, shown best in Fig. 5, is relatively narrow but has its maximum depth adjacent the aperture 11. However, the groove is tapered in the direction in which it extends from the aperture 11 toward the opening in the top of the container 5 so that it becomes wider and more shallow toward its upper extremity. To support the member 14 within the container, a pair of slots 17 and 18 are provided along opposing wall portions of the container and as shown in Figs. 1 and 3, the member 14 has lateral edge portions that fit within the slots (see Fig. 3). As shown in Fig. 1, the plane portion of the surface 16 in which the groove or channel 16a occurs extends so closely to the elements 10 as to be almost in contact with them. Due to the reduction in depth of the groove 16a, the total thickness of the member 14 may vary in the manner shown whereby the thickness of the end-portion of member 14 adjacent the inlet port is greater than that at its upper extremity. The plane portion of the surface 16 extends closely and almost into tangency with the rounded surfaces of the elements 10. The grooved portion of the surface, i. e., surface 16a, extends in such a pattern relative to the upper surface of the elements as to obtain a desired or predetermined pattern of liquid distribution relative to the elements. The elements 10 of which one is shown in detail in Fig. 4 are supported within a pair of slots 19 and 20 which occur in opposite wall-portions of the container. Each element comprises an intermediate elongate portion 22 and end-portions 23 and 24 of greater diameter than the intermediate portion. The larger diameter of the end-portions establishes the spacing of the intermediate portions of adjacent elements when supported within the

slots 19 and 20 with the surfaces of the end-portions of adjacent elements in contact. The elements may be inexpensively constructed of glass-rod stock in gradually increasing lengths in accordance with the divergency of the side walls of the container 5 from which the elements are supported. The end-portions of the glass rods are enclosed by a material that is chemically resistant to the ingredients and the products of reaction occurring in the spinning bath discharged from the tube 7. The enlarged end-portions of the glass rods may be formed expediently by wrapping them with a plastic tape or film comprising a material such as polyethylene, or one of the vinyl resins. Small cups or caps of suitable inside diameter may be molded from one of these organic plastic materials and applied to the glass rods.

If preferred, solutions or latices of these materials may be prepared and applied as coatings in one or more applications. As long as the slots 19 and 20 are constructed to widths that provide a loose but close fit with respect to end-portions of the elements 10, such elements may be loosely supported within the slots since there is little inclination for them to be forced out of position by the movement of a yarn 25 thereof or the liquid passing therebetween. However, the elements may be also cemented in place within the slots 19 and 20. If preferred, the elements may be constructed without enlargement of the end-portions and the end-portions inserted during assembly of the separator into a series of spaced holes provided in place of each slot. The spacing in the elements with respect to each other is not critical. However, in the practice of the invention the glass rods used in constructing the elements were wrapped with a polyvinylchloride strip to obtain an increase in thickness of approximately 0.020 inch. The widths of the resulting gaps between the intermediate portions of the adjacent elements were thus approximately 0.020 inch.

The container 5 has an upper extension 28 for supporting a guide device 29 comprising a block 31 and pins 32 and 33. The device 29 is constructed preferably of 40 corrosion and abrasion resistant materials; for example, the pins may comprise glass and the block may be fabricated from glazed ceramic ware. During operation, the yarn 25 passes between the pins as it leaves the device, and the path of the yarn through the device is thus properly aligned through the region extending between the upwardly-facing surfaces of the elements 10 and the channeled surface 16 of the partition member 14. The guide device 29 also implements and continues the stripping of liquid from the strand. The extension 28 slopes 50 toward the interior of the compartment 5 and thus drains any liquid removed by the guide 29 into region contiguous with the outlet port 9.

In the normal use of the device generally illustrated by Fig. 1, a yarn and a liquid are discharged from the tube 7 into the region overlying the elements 10 at a desired velocity, for example, a velocity within the range of 50 to 150 meters per minute. As the channeled portion of the surface 16 slopes gradually in toward a plane tangent to the surfaces of the elements, a lateral pressure is applied to the liquid which urges it between the elements. The channel while tapering to less depth also tapers to greater width so that the liquid is distributed in a direction lateral with respect to the movement of the strand above and lengthwise of the elements 10. The space between the elements available for passage of the liquid to the drainage space at the other side thereof as the strand and the liquid advance progressively over the elements becomes greater with the increasing width of the channel so as to facilitate more complete and rapid separation of the liquid from the yarn.

An important advantage of the device of the present invention is that the partition member 14 may be removed to facilitate the lacing of the strand through the container. For example, when the spinning of a viscose

70 yarn is commenced, a stream of liquid and strand is discharged from the tube 7 into the container 5. With the member 14 removed, a body of the liquid, with the lead portion of the strand floating therein, accumulates in the region of the container above the inlet port at 11 and the elements 10. The liquid entering the container is, of course, under no lateral constraint and, consequently, does not flow as rapidly between the elements 10 as during normal operation. The level of the liquid remains at a substantial height within the above mentioned region. The strand may be readily captured while floating within this body of liquid and then laced through the guide 29. Thereupon, the member 14 is inserted into place to obtain normal functioning of the device.

The device herein described is advantageously used in conjunction with vertical-tube spinning apparatus since the outlet extension 9 is adapted for receiving the liquid by gravity. However, the orientation of the device as illustrated is not critical in availing to the operator most of the advantages which may be derived therefrom in the processing of yarns. The device of the present invention permits the stripping of liquid from yarn with a minimum of filament breakage and abrasion. There is little, if any, tendency for filament to wrap any portion of the device engaged by the yarn. The device has a further advantage in that the portions of the stripping elements engaged by the yarn are maintained in wet condition and not subject to deposition of solid materials carried in suspended or dissolved form within the liquid. The device is cheaply and readily constructed of any one of the many corrosion resistant organic thermoplastic and thermo-setting resins of synthetic origin currently available, hard rubber, or lead. Portions such as the elements 10 and the pins 32 and 33 are preferably fabricated from abrasion-resistant materials such as those mentioned.

While a preferred embodiment of the invention has been shown and described, it is to be understood that changes and variations may be made without departing from the spirit and scope of the invention as defined in the appended claims.

I claim:

1. A device for separating liquid from a running strand while traversing a substantially fixed path extending through the device comprising means having a group of rounded elongate upwardly-facing convex surfaces disposed in substantially-parallel closely-spaced series relationship underneath, and progressively along, said path, means disposed above said path having a downwardly-facing surface in closely-adjacent relationship with said upwardly-facing surfaces, a longitudinal portion of the downwardly-facing surface extending along said path and being recessed, such surface portion defining a passageway along the path between both of said means, and a duct for supplying a running strand and a stream of liquid moving concurrently therewith to one end of the passageway, said recessed surface portion defining at the other end of the passageway an opening for discharging the strand from the passageway, the recessed surface portion being progressively more shallow in a direction extending from the duct toward the opening, said means disposed underneath the path comprising means for draining the liquid downwardly from said surfaces.

2. A device for separating a liquid from a running strand while traversing a substantially-fixed path extending through said device comprising means having a group of rounded elongate upwardly-facing convex surfaces disposed in substantially-parallel closely-spaced series relationship underneath, and progressively along, said path, means disposed above said path having a downwardly-facing surface in closely-adjacent relationship with said upwardly-facing surfaces, a longitudinal portion of the downwardly-facing surface extending along said path and being recessed to define a passageway along the path between both of said means, and a duct

for supplying a running strand and a stream of liquid moving concurrently therewith to one end of the passageway, said recessed surface defining at the other end of the passageway an opening for discharging the strand from the passageway, the recessed surface portion being progressively wider and more shallow in a direction extending from the duct toward the opening, said means underneath the path comprising means for draining the liquid away from said surfaces.

3. A device for separating liquid from a running strand while traversing a substantially fixed path extending through the device comprising means having a group of rounded elongate upwardly-facing convex surfaces disposed in substantially-parallel closely-spaced series relationship underneath, and progressively along, said path, means readily detachable from the remainder of the device disposed above said path and having a downwardly-facing surface in adjacent relationship with said upwardly-facing surfaces, means for detaching the last-named means, a longitudinal portion of said downwardly-facing surface extending along said path and being recessed, such surface portion defining a passageway along the path between the first-named means and the second-named means, a duct for supplying a running strand in a stream of liquid moving concurrently therewith to one end of the passageway, said recessed surface portion defining at the other end of the passageway an opening between the first-named means and the second-named means through which the strand may pass from the passageway, the recessed surface portion being progressively more shallow in a direction toward the opening to progressively reduce the cross section of the passageway whereby liquid discharged from the duct is forced downwardly between said upwardly-facing surfaces, said means underneath the path comprising means for draining the liquid away from said surfaces.

4. A device for separating liquid from a running strand while traversing a substantially fixed path extending through the device comprising upwardly-facing perforate means disposed underneath, and lengthwise of, said path, means disposed above the path having a downwardly-facing surface in closely adjacent relationship with the first-named means, a longitudinal portion of the downwardly-facing surface extending along said path and being recessed, such surface portion defining a passageway along the path between both of said means, a duct for supplying a running strand and a stream of liquid moving concurrently therewith to one end of the passageway, said recessed surface portion defining at the other end of the passageway an opening between the two means through which the strand may pass from the passageway, the recessed surface portion being progressively more shallow in a direction extending from the duct to the opening to progressively reduce the cross section of the passageway whereby liquid discharged from the duct is forced downwardly through the perforate means; the perforate means comprising means for draining the liquid away from the perforate means.

5. A device for separating liquid from a running strand while traversing a substantially-fixed inclined path extending through the device comprising means having a group of rounded elongate upwardly-facing convex surfaces disposed in substantially parallel closely-spaced series relationship underneath, and progressively along, said path, means disposed above said path having a downwardly-facing surface in closely adjacent relationship with said upwardly-facing surfaces, a longitudinal portion of the downwardly-facing surfaces extending along said path and being recessed, such surface portion defining a passageway along the path between both of said means, a duct for supplying a running strand and a stream of liquid moving concurrently therewith to one end of the passageway, said recessed surface portion defining at the other end of the passageway an opening between the two means through which

the strand may pass from the passageway, said path extending in an upward direction from the duct to the opening, the recessed surface portion being progressively more shallow in a direction extending from the duct toward the opening to progressively reduce the cross section of the passageway whereby liquid discharged from the duct is forced downwardly between said surfaces of the lower means, said lower means comprising means for draining the liquid away from said surfaces.

5 6. A device for separating liquid from a running strand while traversing a substantially fixed path extending through the device comprising means having a group of rounded elongate upwardly-facing convex surfaces disposed in substantially parallel closely-spaced series relationship underneath, and progressively along, said path, means disposed above said path having a downwardly-facing surface in closely adjacent relationship with said upwardly-facing surface, a longitudinal portion of the downwardly-facing surface extending along said path and being recessed, such surface portion defining a passageway along the path between both of said means, a duct for supplying a running strand in a stream of liquid moving concurrently therewith to one end of the passageway, said recessed surface portion defining at the other end of the passageway an opening between the two means for discharging the strand from the passageway, means for enclosing a region disposed underneath the first-named means, the recessed surface portion being progressively more shallow in a direction extending from the duct toward the opening to progressively reduce the cross section of the passageway whereby liquid discharged from the duct is forced downwardly between said upward-facing surfaces into said region, outlet means for said region connected to the enclosing means at a level below all of said upward-facing surfaces.

20 7. A device for separating liquid from a running strand comprising a container, a plurality of closely-spaced rounded elongate parallel elements extending between two walls of the container, means disposed above said elements having a downwardly-facing surface in closely-adjacent relationship with the elements, said downwardly-facing surface having a longitudinal portion for enclosing a passageway extending transversely above the elements, duct means extending through a wall portion of the container and terminating at one end of the passageway, said recessed surface portion defining at the other end of the passageway an opening between the elements and the enclosing means for passage of a strand from the passageway, said enclosing means being removably supported between said two walls, the recessed surface portion being progressively more shallow in a direction extending from the duct means toward the opening to reduce the cross section of the passageway whereby liquid discharged from the duct is forced downwardly between said elements, said means having the upwardly-facing surfaces comprising means for draining the liquid away from said surfaces.

25 8. A device as defined in claim 7 wherein the elements are rods and disposed in a substantially planar arrangement between two opposing walls of the container.

30 9. A device for separating liquid from a running strand comprising a container having an inlet port for discharging a stream of liquid and a running strand into the container and an outlet port for discharging the liquid from the container, guide means in spaced relationship with the inlet port for determining the path of the strand through the container, two walls spaced at opposite sides of the path, each wall having a groove extending therealong in a plane common to the groove of the other wall and substantially parallel to the path, said plane of the grooves extending from a wall portion of the container between the inlet port and the outlet port, a plurality of closely spaced rounded parallel rods ex-

tending from the bottom of the one groove to the bottom of the other transversely with respect to the direction of the path, said rods being disposed by the supporting grooves therefor in subjacent relation to the path along a substantial portion of its length, said pair of walls having another pair of grooves, each groove of the latter pair extending along one of said walls closely adjacent a groove of the other pair, the general plane of the latter pair of grooves intersecting a wall portion of the container whereby the inlet port is included between the two planes of both pairs of grooves, and a partition member supported within the latter pair of grooves for enclosing a space contiguous with the inlet port immediately over said rods to place the liquid entering the space under lateral constraint whereby it is urged between the elements and drained into the outlet port.
